UNITED STATES PATENT OFFICE.

SAMUEL HELLER, OF NEW YORK, N. Y., ASSIGNOR TO L. HELLER & SON, INC., OF NEW YORK, N. Y., A CORPORATION OF NEW YORK.

DESIGN FOR A PRECIOUS, OR SEMIPRECIOUS, OR SYNTHETIC STONE, OR AN IMITATION THEREOF, OR AN ARTICLE OF SIMILAR NATURE.

Application filed January 18, 1923. Serial No. 4,920. Term of patent 3½ years.

To all whom it may concern:

Be it known that I, SAMUEL HELLER, a citizen of the United States, residing at New York city, in the county and State of New York, have invented a new, original, and ornamental Design for a Precious, or Semiprecious, or Synthetic Stone, or an Imitation Thereof, or an Article of Similar Nature, of which the following is a specification, reference being had to the accompanying drawing, forming a part thereof.

In the drawings:

Figure 1 is a plan view of a cut stone embodying my design;

Fig. 2 is an end view thereof; and
Fig. 3 is a side view thereof.

I claim:

The ornamental design for a precious, or semiprecious, or synthetic stone, or an imitation thereof, or an article of similar nature, as shown.

In testimony whereof I affix my signature.

SAMUEL HELLER.
